UNITED STATES PATENT OFFICE

146,619

DESIGN FOR A COMBINATION FLASHLIGHT,
COSMETIC CASE, AND CIGARETTE CASEJoseph Rabinowitch, Los Angeles, Calif., assignor,
by mesne assignments, to Precision Specialties,
Inc., Los Angeles, Calif., a corporation of California

Application November 26, 1945, Serial No. 124,087

Term of patent 7 years

(Cl. D86—10)

To all whom it may concern:

Be it known that I, Joseph Rabinowitch, a citizen of the United States, residing at Los Angeles, in the county of Los Angeles and State of California, have invented a new, original, and ornamental Design for a Combination Flashlight, Cosmetic Case, and Cigarette Case, of which the following is a specification, reference being had to the accompanying drawing, forming a part thereof.

Fig. 1 is a perspective view of the combination flashlight, cosmetic case, and cigarette case in closed position showing my new design;

Fig. 2 is a perspective view thereof in open position;

Fig. 3 is a top plan view thereof in closed position; and

Fig. 4 is a bottom plan view thereof.

I claim:

The ornamental design for a combination flashlight, cosmetic case, and cigarette case, as shown.
JOSEPH RABINOWITCH.
